CLAIM

The ornamental design for a beverage bottle assembly with a tethered paracord closure cap, as shown and described.

DESCRIPTION

FIG. 1 is a top front perspective view of a beverage bottle assembly with a tethered paracord closure cap in its closed position showing my new design;

FIG. 2 is a top elevational view thereof;

FIG. 3 is a right side elevational view thereof; the left side being a mirror image thereof;

FIG. 4 is a front elevational view thereof;

FIG. 5 is a rear elevational view thereof;

FIG. 6 is a top rear perspective view thereof;

FIG. 7 is a bottom rear perspective view thereof;

FIG. 8 is a bottom front perspective view thereof;

FIG. 9 is a top front perspective view thereof;

FIG. 10 is a right side view of FIG. 9; and,

FIG. 11 is a top elevational view of FIG. 9.
